UNITED STATES PATENT OFFICE.

RAYMOND F. NAILLER, OF CLEVELAND, OHIO.

COUPLING FOR ENAMELED PIPES.

No. 880,813.

Specification of Letters Patent.

Patented March 3, 1908.

Application filed July 10, 1907. Serial No. 382,992.

To all whom it may concern:

Be it known that I, RAYMOND F. NAILLER, citizen of the United States, residing at Cleveland, in the county of Cuyahoga and State of Ohio, have invented certain new and useful Improvements in Couplings for Enamelled Pipes, of which the following is a specification.

This invention relates to couplings for enamel pipes, such pipes being particularly useful in mines, paper and pulp mills, chemical works and laboratories, vinegar works, pipe lines, and various other places where acids or chemicals have to be conducted.

It is essential that a coupling be provided which will not allow the acids or other fluids conducted by such pipes to come in contact with any metal, and a particular difficulty has been that each of the various parts used to form the coupling must be of the same thickness throughout, and covered with enamel so as to make it acid and rust proof. It is not meant that the pipe and all the parts of the coupling must be of the same thickness, but that each piece must be of the same thickness throughout itself. It is necessary to have all the metal which is to be enameled of a similar thickness, for the reason that a metal part of varying thickness, if coated with enamel and put in the furnace to be burned would be imperfect, because the thin portion would become heated much more quickly than the thick portion, and as a result if the metal were left in the furnace the enamel on the thin portion would be burned, consequently spoiling the work, and as the thicker portion would not be heated enough if the work were taken out of the furnace when the thin portion were at the proper temperature, the result would also be an imperfect piece of work. This and other reasons prevent the use of pipe or coupling parts having various thicknesses, and the present invention therefore embodies a coupling so constructed that no piece thereof is of varying thickness.

A further feature of the invention is that the coupling is flexible, so as to allow pipe lines which are laid across the country to conform to the contour of the country through which they are laid.

A further object of the invention is to provide a coupling which can be readily applied to the ends of the meeting pipes.

The invention is illustrated in the accompanying drawings, in which

Figure 1 is an end view, partly in section, of the coupling. Fig. 2 is a central longitudinal section. Figs. 3 and 4 are similar views of modifications.

Referring specifically to the drawings, A indicate the sections of pipe, which are expanded or belled at their ends as indicated at a.

B is a ring of metal which fits within the adjacent ends of the pipe sections, but said pipe sections do not meet, because vibration would then tend to chip the enamel off and expose the metal to the action of the acids or liquids being conveyed. A rubber sleeve 70 or packing C fits between the ring B and the expanded ends of the pipe sections.

The ends of the pipe sections are tightened upon the inner ring, or rather the sleeve thereon, by means of exterior flanged clamping rings E. Each of these rings is made in two semi-circular parts connected together by bolts F, for the purpose of allowing the rings to be readily applied to or removed from the pipes. Inasmuch as both ends of each pipe section are belled, the rings must be split in order to be applied. The two rings are drawn together by bolts G, connecting the flanges of the collar or ring sections.

D are segmental copper plates placed between the bells of the pipes and the clamping ring, so as not to injure the enamel.

All of the parts which compose the coupling, and the pipes, are coated with enamel on all sides, as indicated at H, which makes the pipe and coupling acid proof and also proof against electrolysis, the enamel being a non-conductor of electricity.

As may be seen, each of the parts is of the same thickness throughout, and consequently will receive the enamel properly. The bells and clamping rings are concentric, whereby a flexible joint is formed which may be set at various angles to accommodate the pipe line to local conditions.

In Figs. 3 and 4 a modified form is shown, having the same characteristics as the coupling above described, with the exception that instead of the split rings being connected by bolts, one section of the ring has hooks I at the end and the other section has projections J at the end, which engage within the hooks,

and so tighten when the ring is drawn up on the bell of the pipe.

I claim:

1. A coupling for enameled pipes, comprising a plurality of parts connecting the pipe ends, each of said parts being coated with enamel and of uniform thickness throughout.

2. The combination with pipes, of a detachable coupling comprising separable parts 10 around the ends of the pipes, each of said pipes and parts being coated with enamel and of uniform thickness throughout.

3. In a pipe coupling, the combination of pipes having expanded ends, a connecting 15 ring fitting within said ends, and clamping rings fitting upon said ends and connected together, said rings being formed in sections joined together each of the pipes, ends and

connecting ring being coated inside and out with enamel and of uniform thickness 20 throughout.

4. A coupling for enameled pipes, comprising enameled pipe sections having expanded ends, an enameled connecting ring within and between said ends, a packing 25 sleeve between the ring and said ends, enameled clamping rings upon said ends and connected together, and soft metal plates between said clamping rings and the pipes.

In testimony whereof I do affix my signature, in presence of two witnesses.

RAYMOND F. NAILLER.
